ELECTRORESPONSIVE DEVICE

Original Filed Dec. 31, 1936

FIG. 1

UNITED STATES PATENT OFFICE

2,219,157

ELECTRORESPONSIVE DEVICE

Walter J. Zenner, Des Plaines, Ill., assignor to
Teletype Corporation, Chicago, Ill., a corpora-
tion of Delaware

Original application December 31, 1936, Serial No.
118,526. Divided and this application Novem-
ber 15, 1937, Serial No. 174,555

6 Claims. (Cl. 175—336)

This invention relates to printing telegraph apparatus, and particularly to a selector mechanism for the control of such apparatus.

This application is a division of application Serial No. 118,526, filed December 31, 1936, which matured into patent 2,170,316 granted August 22, 1939 to W. J. Zenner.

An object of the invention is to provide a self-aligning mounting for the armature of a selector magnet.

Briefly, the invention contemplates a rockably mounted armature lever which carries the selector magnet armature in spaced and yieldable relation to said lever, so that the armature may rock about its mounting and come into engagement with the pole faces of the magnet without requiring that critical adjustment of the armature lever that is essential to a rigidly mounted armature.

For a full and complete understanding of the invention, and of the manner in which it may be practiced, reference may be had to the following detailed description, taken in connection with the accompanying drawing in which,

Fig. 1 is a top plan view partly broken away, showing a selector mechanism embodying the several features of the invention;

Fig. 2 is an elevational view of the selector mechanism shown in Fig. 1;

Fig. 3 is a sectional view, taken on the line 3—3 of Fig. 1; and

Fig. 4 is a detailed perspective view, partly exploded and partly broken away, showing the salient features of the selector mechanism of Fig. 1.

Referring now to the drawing, in which corresponding reference characters represent identical parts throughout the several views, and particularly to Figs. 1 and 2, reference numeral 10 designates a mounting plate which serves as the foundation of the selector mechanism. Adjacent to one end, mounting plate 10 has secured thereto, by means of clamping screws 11, a selector magnet assembly indicated generally by the reference numeral 12.

Selector magnet assembly 12 includes a bracket 13 through clearance holes in which pass the clamping screws 11. Bracket 13 is movable through an arc, for purposes of adjustment, about an integral cylindrical projection 14 which is disposed in a similarly shaped and correspondingly dimensioned aperture in plate 10, and pivotal movement is effected by rotation of a screw 16, the shank of which threadedly engages

bracket 13 at the opposite end to that which carries pivot projection 14.

Screw 16 is provided with slotted head 17, and in spaced relation to head 17 with flange 18. Plate 10 has fixed thereto and extending upwardly therefrom stud 19, the upper end of which terminates between screw head 17 and flange 18. Stud 19 being thus confined between screw head 17 and flange 18, screw 16 is incapable of axial movement, and when it is rotated, bracket 13 is moved angularly about the axis of projection 14. Screw head 17 is provided with radially extending sockets 21 in the periphery thereof, so that when the selector mechanism is installed in such position that access to the slot by screw driver cannot be had, screw 16 may be rotated by a bar-shaped implement applied to successive ones of the sockets 21, in the manner in which capstans are rotated.

Bracket 13 has magnet core 22 secured thereto by means of screws 23. Core 22 has two arms, each of which supports an electrical winding 24 and terminates in a pole face 26.

An armature lever assembly 31 comprises a bell crank lever having arms 32 and 33. Arms 32 and 33 may be integral, and adjacent to the point of intersection of these arms is secured, by means of clamping block 34 and screws or rivets 36, a thin, flat strip of flexible material, such as spring steel, which is intended to serve as a mounting hinge for the armature lever, and is identified by the reference numeral 37. Spring hinge 37 extends free of armature lever arm 32 and clamping block 34, and the free portion is rigidly secured to bracket 13 by means of clamping block 38 and clamping screws 39. Preferably, arm 32 of armature lever 31 overlaps bracket 13 slightly at the point of clamping of spring hinge 37 in order that endwise movement of arm 33 of the armature lever, due to flexing of spring hinge 37, may be prevented. Fig. 4 affords an enlarged detailed view of the mounting of the armature lever on its spring hinge.

At its free end, armature lever arm 32 supports a floatingly mounted selector magnet armature 41 in a manner clearly indicated in Fig. 4. Referring to that figure, it will be noted that armature lever arm 32 is provided with an aperture 42 which is adapted to receive the shank of a headed screw 43. Preferably, aperture 42 is of such diameter, by comparison with the shank of screw 43, as to be a clearance hole therefor, so that the shank of screw 43 may be capable of shifting about within aperture 42. Lever arm 32 has anchoring pins 44 positioned on opposite

sides of aperture 42 extending above the surface of lever arm 32 which is presented toward the pole face 26 of the selector magnet. A flexible spring member 46 has apertures 47 adapted to fit over pins 44, and a central aperture 48 adapted to be entered by screw 43. Spring member 46 has arms 49 extending clear of armature lever arm 32 in opposite directions, and arms 49 are preferably bent toward pole faces 26. Armature member 41 has a threaded aperture 51 which is threadedly engaged by screw 43, and also has grooves 52 in which the outer ends of arms 49 of spring member 46 are seated. Armature 41 is thus supported on armature lever arm 32 by screw 43 and is maintained in spaced relation to the armature lever arm by spring member 46. A spacer 50 limits movement of armature 41 in the direction of the axis of screw 43. Pins 44 prevent spring member 46 from rotating on screw 43, and grooves 52 confine armature 41 to an upright position. The armature is free to rock in order to align itself with the pole faces 26 when the armature is presented to the pole faces, and a critical alignment of armature lever arm 32, with respect to pole faces 26, is not required.

Arm 33 of the armature lever includes cam follower portion 56 arranged to engage an armature cam 57 included in cam assembly 58 carried by a power-driven shaft 59. At its outer end, lever arm 33 is engaged by one end of a tension spring 61, the other end of which engages a bracket arm 62 adjustably mounted by means of split mounting block 63 and clamping screw 64 to post 66 carried by mounting plate 10. Arm 33 of the armature lever has secured thereto a bracket 67 which has depending arms 68 and 69 positioned on opposite sides of lever arm 33 to serve as spring supports in a manner which will be described hereinafter.

In order that the previously mentioned cam assembly 58 may be disposed in a position to present the several cams included therein in operative alignment with levers they are arranged to control, mounting plate 10 is provided with aperture 71 through which shaft 59, which may be driven from any suitable source, such as an electric motor, may project. Shaft 59 has secured thereto spaced discs 72. Between discs 72, cam assembly 58 is mounted on shaft 59 and has at its opposite ends discs 73 fixed to the cam assembly. A friction disc 74, of any suitable resilient material such as felt, is mounted on shaft 59 between each of the discs 72 and the adjacent disc 73. The assembly comprising discs 72, 73, and 74 constitutes a friction clutch through the medium of which rotation may be imparted to cam assembly 58 by shaft 59. In addition to armature cam 57, cam assembly 58 includes a locking cam 76 having a plurality of apices, and a plurality of cam projections 77 arranged helically around the assembly. The functions of cam 76 and cam projections will be set forth hereinafter.

A selector lever assembly 81 includes a mounting bracket 82 adjustably secured to mounting plate 10 in a manner fully described in Patent No. 2,203,300, granted June 4, 1940, to E. W. F. Hanke. It may be stated, however, with reference to the mounting of bracket 82, that screws 83 are clamping screws extending through clearance holes in bracket 82, and screws 84 and 86 have eccentric heads provided for the purpose of adjusting bracket 82. Selector lever 87 is rockably mounted upon bracket 82 by means of a spring hinge 88 similar to spring hinge 37. Spring hinge 88 is clamped to bracket 82 by means of

clamping block 89 and clamping screws 91, and to selector lever 87 by means of clamping block 92 and clamping screws 83. Selector lever 87 may have cooperating therewith detent arm 94 pivotally supported at 96 in the manner fully described in the above identified patent of E. W. F. Hanke. Selector lever 87 may also have at its free end locking lug 97 which is adapted to be blocked under certain conditions by locking blade 98 of locking bell crank lever 99. This bell crank 10 has one arm engaging cam 76 and is adapted to be rocked clockwise each time one of the apices of the cam is presented to the bell crank.

Selector lever 87 is provided with depending arms 101 and 102, which, as shown in detail in Figs. 3 and 4, cooperate with depending arms 68 and 69 of bracket 67 secured to armature lever arm 33 to support centering springs by means of which selector lever 87 is caused to follow the selective conditions established in the armature 20 lever. Thus, tension spring 103 extends between arms 68 and 102, and tension spring 104 extends between arms 69 and 101. The tension of springs 103 and 104 is such that selector lever 87 tends to be positioned midway between arms 68 and 69 25 of armature lever arm 33.

Selector lever 87 is provided at its free end with spaced depending arms 106 which are effective to control the several elements of a sword and T-lever selector mechanism designated generally by the reference numeral 107. Sword and T-lever selector 107 comprise a plurality of thin, flat selector fingers or sword levers 111 and an equal number of T-levers 112 individually aligned with the selector fingers 111. The selector fingers 111 are individually supported by spacer plates 113 which also separate the T-levers 112 and which are mounted on studs 114 carried by mounting plate 10. Each of the selector fingers 111 has at its left-hand end, as viewed in Fig. 1, 40 a disc-like portion 116 which is fitted into a correspondingly shaped aperture in a selector finger operating bell crank lever 117 pivotally mounted on a pivot pin 118. Each of the bell crank levers 117 is arranged to be rocked counterclockwise by 45 one of the cam projections 77 included in selector cam assembly 58. Adjacent to the disc-like portion 116, each selector finger or sword lever 111 is provided with oppositely extending arms 119 which terminate in abutments 121.

T-levers 112 are rotatably mounted upon pivot pin 122 carried by mounting plate 10, and each of the levers is provided with an arm 123. Arm 123 terminates in disc-like portion 124. T-levers 112 are intended to be articulated by means of 55 the disc-like portions 124 to code bars, code discs, or other permutation code elements (not shown), as disclosed in Patent No. 1,745,633, granted February 4, 1930, to S. Morton et al. Selector lever 87 is adapted to be rocked, in a manner which will 60 be described later, through an arc sufficient to bring one or the other of its arms 106 into the path of one or the other of abutments 121 of selector fingers 111, as those fingers are reciprocated leftwardly by the associated bell crank levers 117, and such angular movement of selector lever 87 is sufficient to bring locking lug 97 from one side to the other of locking blade 98 carried by locking bell crank 99. Continued reciprocation of a selector finger 111 after one of its abutments 121 has engaged one of the depending arms 106 of selector lever 87 causes the selector finger to move angularly about the center of its disc-like portion 116 to bring its free end into engagement with its associated T-lever 112 at the opposite 70 75

side of the pivotal mounting 122 thereof. The angular movement of selector fingers 111 is limited by stop pins 126 carried by mounting plate 10.

The rotation of selector cam assembly 58 by shaft 59 is controlled by a stop gate 131 which is periodically presented in blocking condition in the path of a stop arm 132 rigidly secured to selector cam assembly 58. Stop gate 131 is pivotally supported by stud 133 carried by plate 134 which is pivoted by means of pivot screw 136 to plate 137 rigidly secured on posts 66. An arm 138 mounted on pivot screw 136 above plate 137 has extending therethrough the shank of a knurled-headed screw 139 which threadedly engages stop gate mounting plate 134. Plate 134 may be adjusted pivotally about pivot screw 136 to vary the location of stop gate 131 and may be clamped in any desired position of adjustment by drawing plate 134 and arm 138 into clamping engagement with plate 137 by means of screw 139.

Stop gate 131 has an arm 141 which is presented in the path of cam assembly stop arm 132 when the stop gate is in its extreme clockwise position, and a spring (not shown) biases stop gate 131 so that it tends to rotate into its extreme clockwise position. The stop gate may be locked in the position to which it tends to be rotated by the engagement of a shouldered portion 30 of latch lever 142 with arm 143 of the stop gate. Lever 142 is mounted on stop gate mounting plate 134 by means of pivot 144 and is normally urged into locking engagement with arm 143 of stop gate 141 by compression spring 146. 35 A bell crank 147 pivotally mounted on bracket 148 carried by plate 137 has one arm 149 engaging stop gate locking lever 142 at the end opposite to the shouldered portion which engages stop gate 133, and has another arm 151, the free end 40 of which is disposed in a notch in the free end of armature lever 31 (Fig. 1).

In the rest condition of a selector mechanism, such as the one shown herein, when the mechanism is prepared to respond to incoming telegraph signals, but signals are not on the telegraph line, a continuous energizing current is applied to winding 24 of selector magnet 12, which causes its armature 41 to be attracted to its pole face 26. Since armature 41 is yieldingly mounted on arm 32 of armature lever 31, it is not essential that arm 32 be adjusted into exact parallelism with pole faces 26, because the armature is free to rock about its one-point mounting and engage both pole faces, even if 45 armature lever arm 32 should happen to be twisted or bowed. As long as armature 41 is held attracted by the selector magnet 12, the armature lever is held in its extreme counterclockwise position (as viewed in Fig. 1). In this condition of the selector mechanism, bell crank 147 and latching lever 142 are held in their extreme counterclockwise and clockwise positions respectively (as viewed in Fig. 3), and stop gate 131 is locked in the position in which its arm 141 is 50 disposed in the path of and blocks stop arm 132 carried by selector cam assembly 58. The cam assembly is thus held stationary despite the torque applied to it by continuously rotating shaft 59 through discs 72, 73, and 74. In the 55 rest position of cam assembly 58, a low portion of armature cam 57 is presented toward follower 56, which is out of engagement with cam 57 as a result of presentation of armature lever 31 in its counterclockwise position.

75 Printing telegraph mechanisms of the type for

which the selector mechanism herein described is especially adapted are customarily operated on permutation code combinations of marking and spacing impulses, the former represented by energization of the selector magnet and the latter represented by deenergized condition of the magnet. Each permutation code combination of impulses is preceded by a start impulse which partakes of the nature of a spacing impulse, whereby the selector magnet becomes deenergized. 10 When the start impulse is received, the armature lever is restored to its extreme clockwise position by tension spring 61, and its movement to that position results in (referring to Fig. 3) clockwise rotation of bell crank 147, and counterclockwise rotation of latching lever 142 in opposition to compression spring 146, whereby the latching shoulder of lever 142 is withdrawn from latching engagement with arm 143 of stop gate 131. With stop gate 131 unlatched, only 20 its biasing spring (not shown) opposes the torque imparted to cam assembly 58 and its stop arm 132 by shaft 59. The resistance furnished by the biasing spring being relatively insignificant, cam assembly 58 responds to its torque, 25 stop arm 132 escapes from the stop gate 131 by rocking it, and the cam assembly rotates through one cycle during the reception of a code combination.

Periodically in timed relation to the signal impulses armature cam 57 rocks armature lever 31 counterclockwise to bring its armature 41 into engagement with pole faces 26, and if a marking signal is then applied to the selector magnet, the armature 41 and armature lever 31 30 will be held in opposition to tension spring 61. If, instead, a spacing signal is then applied to the selector magnet, the armature lever returns to its extreme clockwise position as soon as its follower portion 56 escapes from an apex of armature cam 57. Thus, under the joint control of armature cam 57 and selector magnet 12, the selective positions of armature lever 31, corresponding to successive signal impulses, are determined. After each selective position is determined, one of the apices of locking cam 76 40 rocks locking bell crank 99 to unlock selector lever 87. When selector lever 87 is unlocked, it responds to any condition of unbalance between springs 103 and 104 resulting from presentation of armature lever 31 in a particular selective position to shift selector lever 87 to a corresponding selective position.

The several selector cam projections 77 are arranged with respect to the apices of the locking cam 76 to actuate their associated bell cranks 117 to draw the selector fingers 111 leftwardly (Fig. 1) after the unlocking, selective setting and relocking of selector lever 87. As each selector finger 111 is drawn leftwardly, one or the other 55 of the depending arms 106 of selector lever 87 is presented in the path of the corresponding abutment 121 of the selector finger. If the selector lever occupies a different selective position than it did at the corresponding instant in the preceding signal combination, an abutment 121 will engage an arm 106 before finger 111 completes its leftward movement, and in completing such movement, it will be rocked about its disk-like portion 116 to shift its free end to the opposite side of the pivotal mounting 122 of T-levers 112. Upon the restoration of the sword lever 111 to its extreme right-hand position, it rocks the associated T-lever to a new selective position.

In the manner described in the foregoing para- 75

graph, the several T-levers 112 are positioned permutatively in accordance with a received code signal combination. As each T-lever 112 is positioned in accordance with its code impulse, its 5 associated code disc or code bar (not shown) is positioned permutatively as described in Patent No. 1,745,633 to control the selection of selectable elements.

The leaf spring or spring hinge mountings for 10 the armature lever 31 and the selector lever 87 are employed in substitution for the pivots disclosed in Patent No. 1,937,376 granted November 28, 1933, to W. J. Zenner. Frictional pivots may possibly, under some conditions, suffer excessive 15 wear due to friction, with the result that the desired center of pivotal movement of the lever is not maintained. With the torsional pivots afforded by the flat springs, the rapid alternate clockwise and counterclockwise rocking of the 20 levers is devoid of frictional wear upon the supports for those levers.

Brief mention was made in the detailed description of the invention, of the overlapping of the armature supporting arm, and the portion 25 of bracket 13 to which leaf spring hinge 37 is clamped, for the purpose of preventing endwise movement of arm 33 of armature lever 31. It will be observed that when the selector magnet holds armature lever arm 33 out of engagement 30 with cam 57, spring 61 may tend to rotate lever arm 33 clockwise about the resilient mounting of armature 41 to the extent that flexing of leaf spring hinge 37 would permit. By providing overlapping relation between the armature lever arm 32 and the spring hinge supporting portion of bracket 13, the attracted armature lever arm 32 cannot rock clockwise upon screw 43 because bracket 13 blocks the end of the lever arm to which the spring hinge is connected. It will be 35 understood that should different interconnections between the armature lever and selector lever than centering springs be employed, or should other modifications be made which might result in tendencies of either of the levers to rock in 40 undesired paths, such tendencies may be obviated by introducing positive blocking relation between adjacent members at the point or points of clamping of the spring hinges in accordance 45 with the principle underlying the overlapping of lever arm 32 and bracket 13.

Although a specific embodiment of the invention has been disclosed and described herein, it is to be understood that the invention is not limited to such embodiment, but is capable of modification, rearrangement and substitution of parts 55 and elements within the scope of the appended claims.

What is claimed is:

1. In an electroresponsive device, an electromagnet, an armature therefor, a lever arm having an aperture therein, a shouldered screw having the shank extending loosely through said aperture and supporting the armature in fixed 60 relation to said screw, and a compression member loosely supported on the shank of said screw and having arms abutting the lever arm and other arms yieldably and slidably abutting the armature.

2. In an electroresponsive device, an electro-

magnet, an armature therefor, and means for yieldingly supporting said armature for universal rocking movement including a lever arm having an aperture therein, a shouldered screw having the shank extending loosely through said aperture and engaging the armature, a compression member loosely supported on the shank of said screw intermediate the lever arm and the armature, said compression member having a plurality of sets of arms, means establishing interconnection between one set of arms and said lever arm for preventing rotation of said compression member, and means establishing interconnection between another set of arms and said armature for preventing rotation of said armature upon the 15 axis of said shouldered screw.

3. In an electroresponsive device, an electromagnet, an armature therefor, a cyclically operable lever arm having an aperture therein, a shouldered screw having the shank loosely extending through said aperture and engaging the armature, a resilient compression member loosely supported on the shank of said screw intermediate the lever arm and the armature for absorbing overtravel of said lever arm and irregularities in alignment and comprising a plurality of sets of arms, one pair of said arms having interconnection with said lever arm, said armature having a plurality of grooves in one face thereof in which the arms of another set are disposed. 30

4. In an electroresponsive device, a mounting plate, a bracket having a projection pivotally engaging said plate, an electromagnet secured to a portion of said bracket, a block secured to another portion of said bracket, a flexible metallic strip having a portion at one end clamped to said bracket by said block, an armature lever clamped to a portion of the other end of said strip, the middle portion of said strip extending across the axis of said pivotal projection, and 40 means for shifting said bracket about said pivotal projection.

5. In an electroresponsive device, a mounting plate, a bracket having a projection pivotally engaging said plate, an electromagnet supported by a portion of said bracket, a block supported by another portion of said bracket, a flexible metallic strip having an end portion secured to the block carried by said bracket, an armature lever clamped to the other end portion of said strip with the end of the armature lever overlapping said block and the middle portion of said strip extending across the axis of said pivotal projection, and means for rocking said bracket about said pivotal projection. 50

6. In an electroresponsive device, a mounting plate, a bracket having a projection pivotally engaging said mounting plate, an electromagnet supported by said bracket, an armature lever pivoted substantially coaxially with the pivotal engagement of said bracket with said mounting plate, means for rocking said bracket and electromagnet about said projection, an armature carried by said armature lever for universal rocking movement with respect thereto, and yieldable means interposed between said armature lever and said armature for absorbing variations in alignment and air-gap between said electromagnet and said armature. 60

WALTER J. ZENNER. 70
